UNITED STATES PATENT OFFICE

WASHINGTON SABATINI, OF ONEGLIA, ITALY

DEVICE FOR WORKING OUT CALCULATIONS IN CONNECTION WITH STRUCTURES OF REINFORCED CONCRETE

Application filed December 16, 1925, Serial No. 75,844, and in Italy January 13, 1925.

This invention relates to a machine for calculations in connection with constructional problems in reenforced concrete based upon the mechanical application of formulæ referring to calculations for reenforced concrete laid down in a hand book composed by the present applicant and published by the Editor Ulrico Hoepli of Milan. These formulæ are reduced to the simplest possible expression 10 and represent the fundamental conception for the construction of the present device for calculations in connection with reenforced concrete.

These formulæ express the dimensions of 15 the concrete and of the iron as well for floors and their girders and tanks as a function of only one or of two variables.

The machine according to the present invention essentially consists of two cylinders 20 to which is imparted a reciprocating and a rotary motion by means of two buttons of which each one is rotatably arranged in the centre of a disc supplied with two groups of concentrically arranged holes. The inner 25 holes of the left hand disk correspond with the dimensions of floors and of tanks, the outer holes with those of girders. The inner holes of the right hand disc correspond with the weights of the floors and with the height 30 of the tanks, the outer holes with the weights of the girders. Each button carries two keys mounted upon a radially movable arm one key of which is adapted to be engaged with the inner holes while the other key 35 engages with the outer holes of the disc.

It therefore results that with each position of the two thumb buttons there corresponds one point only upon the surface of each cylinder; upon the cylinders are indicated the required 40 solutions and by a perfect correspondence between the rotary and reciprocating motion of the cylinders and the rotary motions of the buttons any point of its surface can be brought in front of two suitable reading slots through which the solutions can be read. One cylinder has marked thereon 45 the solution of the floors and of the tanks as a function of two variables and the heights of the girders as a function of only one 50 variable. The other cylinder has indicated

thereon the solutions of the dimensions of iron of the girders as a function of two variables.

Reference will now be made to the accompanying drawings, in which:—

Figure 1 is a top plan view of the device;

Figure 2 is a top plan view of the device with the cover removed;

Figure 3 is a front elevation of the device with the front wall removed;

Fig. 4 is a vertical sectional elevation according to line 4—4 of Figure 1 without the buttons and without the perforated discs;

Figure 5 is an end elevation of the device with the side wall removed;

Figure 6 is a vertical sectional end view according to line 6—6 of Figure 1 without the buttons and the perforated discs.

Figures 7 and 8 show tables adapted to be applied upon the two cylinders.

In these figures in which like numbers indicate like or similar parts, the device, enclosed in a rectangular box comprises two metallic discs fastened on the cover arranged side by side of which the disc 1 at the left 75 carries two concentric groups of holes, the inner 20 of which corresponds with the dimensions of the floors and of the tanks and the outer one corresponds with dimensions of the girders. In the centre of this disc 80 there is rotatably supported a button 2 carrying a rotatable arm which is provided with two keys 4, an outer and an inner key either of which by the movement of the arm can be brought into engagement with the outer or 85 inner group of holes respectively. The button 2 of the left hand disc is fastened upon the vertical shaft 5 and its rotation is imparted by the helical wheel 6 simultaneously to two helical wheels 7, 7 which transmit to 90 the cylinders 8, 8 a like rotary motion in opposite directions.

The metallic disc 1' at the right-hand side is also provided with two groups of concentric holes of which the inner group 22 corresponds with the weights of the floors and with the height of the tanks and the outer group 23 corresponds with the weights of the girders. The button 2' of this disc carries also a rotatable arm 3 which arm is provided 100

with two keys 4', an outer and an inner key which, by the movement of the arm, can be engaged with the outer or inner group of holes respectively. The button 2⁷ of the 5 right-hand disc is fastened on the vertical shaft 9 which carries at its lower end a toothed wheel 10 in engagement with the two racks 11, 11 which are connected with the cylinders 8, 8 so as to impart to them a reciprocating opposite motion when one button is 10 rotated and without preventing the rotation of the cylinders when driven by the rotation of the other button.

The cylinders 8, 8 have tables on their 15 peripheral surfaces as shown in Figures 7 and 8. These tables represent in the case of the lower cylinder thicknesses of concrete for floors and tanks, sections of iron for floors and tanks, and heights of girders while the 20 table on the upper cylinder represents sections of iron for girders.

The cylinders 8, 8 with their tables marked thereon are adapted to pass respectively behind reading slots 12' and 13', which slots are 25 uncovered by openings in discs 17 and 18 controlled respectively by buttons 12 and 13. An arrow 19 is marked on each disc so that by rotating for example the disc 17 operated by the button 12 and in bringing the arrow 30 in a direction towards the right, towards the bottom and towards the left in the reading slot 12', there will be read respectively the height of the girder, the thickness of the floor and the section of the iron of the floor.

35 Similarly the button 13 operates the disc 18 and in bringing its arrow 19 upwardly in the reading slot 13', there will be uncovered a number which indicates the total section of iron of the girder.

40 The numbers of the tables carried by the cylinders 8, 8 which appear in the reading slots 12', 13' show a point at the left or right or below the number. This renders it possible to simplify the table as each point indicates a decimal and constitutes a conventional 45 means adopted by the inventor. For instance .19 indicates 19.25; 1.4 indicates 14.5 and 4. indicates 4.75.

The point to the left of the number, indicates 50 0.25, the point below the number 0.5 and the point to the right 0.75 which decimal fractions will have to be added to the number.

55 Two examples will now be given relating to calculations for a floor, and a girder

To calculate for example, a floor of 3 meters span with a load of 200 kilo per square meter.

60 The button 2 is rotated to the point of the inner row of holes which corresponds with 3m; then the button 2' at the right is rotated to the point at the inner row of holes which corresponds with the load 200 kilo. Then the button 12 is rotated in a position in which 65 the arrow 19 is directed towards the bottom

and in the reading slot 12' is read 4 that is 4 square centimeter, which represents the section of the iron requested for a meter width of the floor. Then the button 12 is rotated in a position so that the arrow 19 on it is directed towards the right and in the reading slot is read 11, that is, 11.75 square centimeter which is the total thickness of the floor. 70

To calculate for example a girder with a span of 5 meters and which has to carry a total load of 3000 kilo (weight of floor and load). 75

The button 2 at the left is rotated and brought over the number 5 of the outer group of holes indicating the span of the girder and the button 2' at the right is brought over the 80 number of the outer group of holes which indicate the load of 3000 kilo; then the button 13 is rotated so that the arrow 19 is directed against the left and in the reading slot 13' will appear the number 8 which indicates 85 the section in iron in square centimeter.

In order to establish the height of the girder the button to the left is unaltered and the button to the right brought upon the letter T which is a constant of the machine. 90 Then the button 12 will be rotated so that its arrow 19 will be directed towards the left. In this position of the button 12, its disc uncovers in the sight slot 12' the number 20 that is 20 centimeter of height of the girder. 95

It is evident that the device can also serve for the solution of similar problems, in which as in the calculation of a floor or of a girder the result can be expressed by simple formulae with one or two variables.

Having now particularly described and ascertained the nature of my said invention and in what manner the same is to be performed, I declare that what I claim is:—

A calculating device of the character described, including in combination a pair of cylinders marked with the required solutions, buttons, a rotatable arm associated with each button, gearing interposed between the buttons and cylinders for imparting a rotary motion and a reciprocating movement alternately to said cylinders so as to rotate or reciprocate them with equal speed in opposite directions, and graduated discs each provided with two groups of concentric holes serving 105 as setting points for the adjacent rotatable arm of each button and said holes corresponding to points on the cylinders which represent the required solution 110

115 In testimony whereof I have signed my name to this specification.

WASHINGTON SABATINI.
